(57) **CLAIM**

I claim the ornamental design for a faucet, as shown and described.

DESCRIPTION

FIG. 1 is a top plan view of a first embodiment of the faucet showing my new design with the phantom lines depicting environmental structure and forming no part of the claimed design;

FIG. 2 is a front elevational view thereof with the phantom lines depicting environmental structure and forming no part of the claimed design;

FIG. 3 is a left side elevational view thereof with the phantom lines depicting environmental structure and forming no part of the claimed design, the right side being a mirror image;

FIG. 4 is a top plan view of a second embodiment of the faucet of the present invention showing my new design with the phantom lines depicting environmental structure and forming no part of the claimed design;

FIG. 5 is a front elevational view thereof with the phantom lines depicting environmental structure and forming no part of the claimed design; and,

FIG. 6 is a left side elevational view thereof with the phantom lines depicting environmental structure and forming no part of the claimed design, the right side being a mirror image.
